UNITED STATES PATENT OFFICE.

DAVID L. SUMMEY, OF WATERBURY, CONNECTICUT, ASSIGNOR TO SCOVILL MANUFACTURING COMPANY, OF WATERBURY, CONNECTICUT, A CORPORATION OF CONNECTICUT.

PLANT FOR TREATING METAL ARTICLES.

Application filed July 28, 1923. Serial No. 654,294.

To all whom it may concern:

Be it known that I, DAVID L. SUMMEY, a citizen of the United States, residing at Waterbury, county of New Haven, and State of Connecticut, have invented certain new and useful Improvements in Plants for Treating Metal Articles, fully described and represented in the following specification and the accompanying drawings, forming a part of the same.

This invention relates to plants for treating metal articles. More particularly, the invention relates to plants for annealing, cooling and finishing metal articles.

It is the principal object of the invention to provide a plant for treating metal articles efficiently and economically and with a minimum manual labor requirement.

With this general object in view the invention consists in the combinations, details of construction and arrangements of parts which will first be described in connection with the accompanying drawings and then more particularly pointed out.

25 In the drawings—

Fig. 1 is a view in vertical longitudinal section of one end of a metal treating plant constructed in accordance with the invention;

30 Fig. 2 is a view in side elevation showing the other end of the plant;

Fig. 3 is an enlarged transverse sectional view through the annealing furnace;

Fig. 4 is a bottom plan view of part of the 35 conveyor chain;

Fig. 5 is a sectional view taken on the line 5—5 of Fig. 2;

Fig. 6 is an enlarged view in side elevation of the automatic charging mechanism;

40 Fig. 7 is a similar view, with parts in section, of part of the charging mechanism in a different position;

Fig. 8 is a sectional view taken on the broken line 8—8 of Fig. 6;

45 Fig. 9 is a sectional view taken on the line 9—9 of Fig. 7; and,

Fig. 10 is a detail view showing in section part of the charging mechanism.

While plants embodying the invention are 50 capable of a variety of uses, the plant here shown is particularly adapted to the treatment of brass shells or cups. In making various articles of brass, a shell is drawn from

a plate or other blank. The drawing operation may produce shells which go directly 55 to the machines that form the finished product or the shells may require further drawing. In either case, following the drawing operation the shells are treated, this treatment including annealing, cooling, pickling 60 and other finishing operations.

Referring to the drawings, the articles are annealed or otherwise treated in a furnace 11, here shown more or less conventionally. The furnace shown as an example 65 comprises a main housing 12 having a heating chamber 13 and a paralleling chamber 14 extending longitudinally therethrough. This main housing may be of any suitable construction and the heating chamber 13 may 70 be heated in any suitable manner, for example, by electric resistor elements such as shown in a copending application of this applicant, filed July 28, 1923, Serial No. 654,295. If desired the second chamber may be heated 75 also. At one end of the furnace, the left end in Fig. 1, is a supplemental housing hood 15 which encloses a charging chamber 16 which communicates with the longitudinal chambers 13, 14. At the other end of the 80 furnace a supplemental housing hood 115 encloses a discharge chamber 116, also communicating with the longitudinal chambers. As here shown the hood 15 rests directly on the furnace foundation 10 and the discharge chamber 116 is sealed at the bottom by means of a cooling tank to be described.

85 There is provided means for transporting the articles to be treated through the furnace at such speed as to enable the heat treatment, such as annealing, to be accomplished. As here shown as an example, extending through the heating chamber 12 are a pair of rails 17 on which slide conveyor buckets 18. Each bucket has on one side a pair of perforated lugs 19 and on the other side a pair of perforated yokes 20. The lugs of one bucket are inserted in the yokes of the next bucket and suitable pivot pins 21 passing through the lining perforations connect the buckets to form an endless conveyor chain. The bucket bottoms have guide lugs 22 which coact with the rails (Fig. 3) to keep the chain properly positioned. At the charging end of the furnace the buckets 100 pass over two complementary hexagonal pul-

leys 23 located in the charging chamber 15 and mounted on a shaft 24. As appears in Fig. 1, the rails 17 extend into the charging chamber to cooperate with the pulleys so that the buckets can pass from the uppermost faces of the pulleys directly onto the rails. At the discharge end of the furnace, the bucket chain passes over two hexagonal pulleys 25 located in the discharge chamber 10 116 and mounted on a shaft 26. As shown in Fig. 1, the rails 17 extend outwardly toward the pulleys 25 so that the buckets can pass directly from the rails to the uppermost faces of the pulleys. As shown in Fig. 8, the faces of the pulleys are shouldered, as at 27, to cooperate with the guide lugs 22 of the buckets. From the lower part of pulleys 25, the inverted buckets pass onto rails 28 located in the return chamber 14, 20 the rails 28 extending into the charging chamber 16 and the inverted buckets pass up around pulleys 23 to take conveying position again. To drive the bucket chain, as here shown as an example, on the shaft 26 is a gear 31 meshing with a pinion 32 on a shaft 33. Also on shaft 33 is a worm gear 34 meshing with a worm 35 driven by a motor 36. The motor is operated and the gearing proportioned so as to move the buckets through 30 the heating chamber 13 at a speed to accomplish proper heating of the articles under treatment, this movement, in the present embodiment, being continuous.

There is provided means for automatically 35 delivering the articles to be treated to the furnace, and in constructions of the type above described, the articles may conveniently be delivered to the buckets while they are in the charging chamber 16. Further, 40 with constructions embodying bucket conveyors as above described, the charging means may conveniently include a measuring hopper. Although capable of various constructions, in that here illustrated as an example, above the pulley shaft 24, so as to be above a bucket as it first takes upright position, is an opening 37 in hood 15. On the hood adjacent this opening is a 45 hopper housing 38 open at the top. Partly in the housing 38 and extending into the chamber 16 through opening 37 are two complementary gates 39 mounted to swing toward and away from each other. To this end, each gate has a hub 40, one being pinned to a rock shaft 41, the other to a rock shaft 42. When the gates are swung to closed position, 50 their lower edges abut against a suspended sill 43. At the ends of the gates 39 are wings 44 which, with the gates, enclose a V shaped space when the gates are closed. As appears in Figs. 6 and 8, the hopper housing has guide walls 45 extending upwardly from the hubs 40 of the gates and 55 guide flanges 46 extending upwardly from the wings 44, so that articles supplied to the open top of the housing are properly confined. As will now be apparent, the gates 39, wings 44 and part of the housing 38 form a hopper of a given capacity and the contents may be dumped upon swinging open the gates. In the present embodiment, this given capacity is substantially the capacity of one conveyor bucket.

While the hopper may be filled in any suitable manner, as here shown as an example, above the open top of the housing 38, is a bin 47 having a funnel-shaped lower portion and a pivotally-mounted bottom door 48. This door may be swung downwardly by means of a handle 49 to the broken line position of Fig. 1. In this position, the door acts as a chute to guide the articles into the hopper. When the hopper is filled the door is closed, closing movement being aided by a counterweight 50. The bin 55 may be kept supplied with articles by means of a dumping barrel 51 on a hoist 52.

As will now be apparent, when the gates 39 are swung apart to open the hopper, the hopper contents can drop by gravity into a bucket. While the gates may be opened in any suitable manner, in constructions embodying the invention to the best advantage, the operation of the opening means is controlled by the relative position of the buckets. For example, there may be provided means tending to open the gates, a latch element for preventing operation thereof and an escapement mechanism for tripping the latch element as each bucket 100 takes a receiving position below the hopper. Although capable of various constructions, as here shown as an example, mounted on the rock shafts 41, 42, are intermeshing segmental gears 53. The shaft 42 extends outwardly from the housing 38 and secured to the extension is a rocker arm 54 having a weighted lower end 55. When the gates are closed, the weight portion 55 of arm 54 is raised above its center of gravity and is normally latched in such position to hold the gates closed. To this end, as here shown as an example, below the weight portion 55 of arm 54 is an arm 56 pivoted to a bracket 57 on hood 15 and having a stop lug 58 which, in the latching position of the arm, holds the weight portion 55 of arm 54 raised (Fig. 6). The arm 56, at the end opposite its pivot, is mounted on a pin 59 carried by a block 60 slideable up and down in the bracket 57. The block 60 is normally connected, by means to be described, with a second block 61 also slideable in the bracket 57. When the connected blocks 60, 61 are moved down, arm 56 is lowered sufficiently 115 to trip lug 58 from latching position. This frees the weight portion 55 of arm 54 which swings down under gravity until stopped by a lug 158 on arm 56, thus rocking shaft 42. Through gears 53, shaft 41 is simultaneously 120

60 65 70 75 80 85 90 95 100 105 110 115 120 125 130

rocked and the gates 39 are swung to open position. This opening of the gates dumps the hopper contents into the bucket below the hopper. In Fig. 6 the gates are shown 5 closed in dotted lines and open in broken lines. Although the buckets are under a continuous advancing movement, this movement is so slow that a bucket can properly receive its charge when the hopper gates are 10 opened.

To lower blocks 60, 61 to trip the latch as just described, in the present embodiment the second block 61 is connected by an adjustable link 64 with a lever arm 65 mounted 15 on a rock shaft 66. Also on this rock shaft 15 is a dog 67 riding on an escapement wheel 68. This escapement wheel is mounted on the end of the pulley shaft 24 beyond a bearing 69 located outside hood 15 and in which the 20 shaft is journaled. The escapement wheel has a number of dog-elevating teeth 70 equal to the number of pulley faces, in this instance, six. The dog is held to its duty by means of a spring 71 connecting lever arm 25 65 and part of the bearing 69.

Referring more particularly to Fig. 6, as the pulley shaft 24 rotates, the escapement wheel 68 rotates in clockwise direction, the dog 67 riding up the successive teeth. As the 30 dog 67 crops off the high point of a tooth 70, it rocks shaft 66 and thus swings lever arm 65 down, which, through link 64, pulls down the blocks 60, 61, to trip the latch lug 58. The escapement wheel is so arranged 35 that the gates are opened when a bucket is in position below the hopper to receive a charge, as above described.

After an operation of the latch-tripping mechanism link 64 will be slowly moved 40 upwardly as the dog 67 starts to ride up the next tooth of the escapement wheel. Means is provided whereby the hopper gates 45 can be closed and the latch reset as soon as a charge has been delivered and regardless of the dog 67. To this end, as here shown as an example, on the lower block 61 is pivoted a trigger 74 having a catch 50 75 adapted to hook over a lug 76 on the upper block 60. Between the two blocks is a spring 77 tending to separate them. When 55 the parts are in weight-latching position (Fig. 6), the trigger 74 is hooked over lug 76 and the two blocks 60, 61 are, in effect, a unit and they move down as a unit under the pull of link 64 above described. During this movement, however, and after 60 the latch lug 58 has been tripped, trigger 74 strikes an adjustable trip screw 78 on the bracket 57 and the trigger is swung to 65 remove its catch 75 from lug 76 (Fig. 7). Thereafter, the upper block 60 is free to move back to former position regardless of the lower block.

To close and re-latch the gates, the operator 65 swings the rocker arm 54, thus rocking

shafts 41, 42 in the reverse direction and swinging the gates to closed position. This movement is aided by a counterweight 142 on the rock shaft 42. This reverse movement of the rocker arm 54, of course, again 70 raises the weight 55 and the block 60 moves upwardly under the force of spring 77 to reset the arm in a position for its lug 58 to latch the weight in raised position. The 75 hopper may now be refilled with another measured charge for the next bucket.

Meanwhile, during the rotation of the pulley shaft 24 and its escapement wheel, the dog 67 has been riding up the next tooth. 80 This dog movement rocks shaft 66 and so 85 pushes up link 64 to elevate block 61. As soon as the block has been raised sufficiently to move the trigger away from the stop screw 78, the trigger is free to swing back to normal position, a spring 79 tending to 90 hold it in such position. Upon further movement of the block 61, the trigger catch 75 slides over lug 76 and the two blocks are again hooked together. A pin and slot connection 80, 81, between the trigger and 95 the block 61 limits the trigger movements. With the construction described, the operator has plenty of time to close the hopper, set the latch and refill the hopper before the next automatic opening operation. It 95 is to be understood that other means for delivering the charges to the buckets may be employed.

After a bucket receives its charge, the continued conveyor movement carries the bucket 100 along the rails 17 into and through the heating chamber 13 where the charge is annealed or otherwise treated, as above described.

There is provided means for cooling the 105 heated articles and means for automatically delivering the articles from the furnace to the cooling means. Although capable of various constructions, in that here shown, extending under hood 115 and into chamber 116 110 is a tank 85 for containing a cooling liquid, for example, water, part of the tank being located under the point where the buckets turn down over pulleys 25. As the buckets approach an inverted position, the 115 contents are automatically dumped out and drop by gravity into the liquid in the tank. The liquid not only quenches the heated articles but cushions their fall. The liquid in the tank also seals the bottom of the discharge chamber and so conserves heat and excludes air. The liquid in the tank may be kept cool in any suitable manner.

There is provided means for preventing 125 the articles from floating on the surface of the liquid in the tank. As here illustrated as an example, just above the liquid level is a perforated pipe 86 for directing sprays of water toward the tank. Shells sometimes tend to float on the surface. The 130

water sprays from pipe 86, however, by filling the shells and driving out the air, cause them to sink.

There is provided means for automatically 5 delivering the articles from the cooling means. As here shown as an example, extending into the tank 85 is an endless conveyor belt 87 which passes around a pulley 88 and over guide rollers 189. The pulley 10 88 is located near the bottom and inner end of the tank so that the upper strand of the belt extends well under the discharge chamber and well below the liquid level. This upper strand is arranged at such an 15 inclined that it emerges from the liquid outside of and beyond the hood 115.

The belt is driven in any suitable manner. As shown, the belt passes over a drive 20 pulley 89 mounted on a shaft 90 supported on a standard 100. On this shaft is a worm gear 91 meshing with a worm 92. The latter is driven through gears 93, 94 from a motor 95. The belt is provided with cleats 96 for engaging the articles and as the 25 upper strands moves upwardly the articles in the liquid are taken by the belt and conveyed thereby out of the liquid to a point removed from the furnace and tank.

There is provided means for concentrating 30 the articles discharged from the bucket in a space adjacent the rise of the conveyor belt. As here shown as an example, below the path of the falling articles is a guiding funnel 97 which extends into the liquid 35 with its bottom edge just above the belt. As the articles fall into the liquid they are concentrated or confined within the space embraced by the funnel and so prevented 40 from drifting about to points where the rising belt would not reach them.

The invention, in its entirety, includes 45 finishing means to the action of which the articles are automatically subjected after delivery from the cooling means. This 50 finishing means may include pickling, soda applying and other finishing operations. Although capable of various constructions, in that here shown as an example, adjacent the point where the belt 87 turns down over the pulley 89, is located a gravity feed chute 99 which receives the articles 55 as they automatically fall from the belt and conducts them to the end of a long finishing drum 101. This drum is rotatably suspended by a plurality of circumferential rings 102 riding in pairs of oppositely disposed grooved rollers 103. It is rotated by means of chains 104 running over 60 sprockets 105, the chains being driven in any suitable manner. Within the drum is a screw conveyor element 106. As the drum rotates, the articles are caused to pass along the same and during such passage are given 65 various finishing treatments.

Below the forward end of the drum is a

tank 107 for containing a pickling liquor. On the drum, positioned to pass through the pickling tank as the drum rotates, is a scoop 108 which scoops up some of the liquor on each rotation. This liquor is 70 delivered to the interior of the drum through a series of holes 109 in the drum wall located radially in line with the scoop. When the scoop reaches an upright position the liquid carried up thereby flows by 75 gravity through the holes 109 into the drum and so over the articles. Beyond the holes 109 and above the tank 107 the drum has a belt of holes 110 extending all the way around the drum and through these holes 80 the pickling liquor flows back to the tank 107. Beyond tank 107 in the embodiment illustrated is a wash-water tank 111 and the drum has a scoop 112 like scoop 108, the wash water being supplied and removed 85 in a manner identical with the circulation of the pickling liquor. Beyond the wash water unit is a soda unit 113 for supplying a soda solution to the articles. This unit is identical with the units described except 90 that the scoop and bands of holes are narrower, as appears in Fig. 2. Beyond this soda unit is a soap solution unit 114 for treating the articles with a soap solution. This unit is identical with the soda 95 unit. As the articles progress through the drum they are first pickled, then washed, then treated with a soda solution and then with a soap solution. Finally they are dried. This may be accomplished in any 100 suitable manner. In Fig. 2 two drying units 115 are illustrated diagrammatically. Beyond the drying units, is a delivery chute 117 by which the articles may be discharged.

In the plant described, certain of the 105 metal furnace parts are made of a material capable of withstanding continued high temperatures. In case heating elements, such as above referred to are used, namely, nickle-chromium alloy resistors, the metal 110 furnace parts may conveniently be made of nickle-chromium alloy also, thus having the same heat resisting characteristics as the heating elements. In the plant here shown, the bucket chain, the upper rails 17, 115 and the discharge pulleys 25 are made of nickle-chromium alloy.

To review the operation, motor 36 rotates, through the gearing described, the pulley shaft 26 and so drives the conveyor chain, 120 the upright buckets moving from the left to right, as viewed in Fig. 1. Assuming that the hopper contains a charge, when a bucket reaches upright position, as illustrated by the bucket shown in section in Fig. 1, the dog 67 drops off the high point of a tooth 70 of the escapement wheel and causes tripping of the latch lug 57 as above described. Weight 55 being released, 125 swings down under gravity and rocks shaft 130

42, thus causing the hopper gates to swing open. Thereupon the measured charge drops by gravity into the slowly moving bucket. Meanwhile, trigger 74 has been 5 operated to permit separation of the two blocks 60, 61 and the operator swings the gates to closed position by means of lever 54, whereupon the latch will be re-set. The operator then opens the bin door and a new 10 charge slides into the hopper. As the escapement wheel rotates, the latch-tripping parts are returned to their former position as above described.

Continued movement of the filled bucket 15 carries the same through the heating chamber 13 for the heat treatment, for example, annealing. As the bucket turns down over the pulleys 25 in the discharge chamber 116 the articles are dumped out and fall into the liquid in tank 85 where they are 20 quenched. The emptied bucket continues its course and slides, inverted, along the rails in the return chamber 14 until it passes up around pulleys 23 to its original charging 25 position. With an endless conveyor moving in a closed furnace there is a material economy in heat requirements and with a continuously moving conveyor excessive motive power requirements are avoided.

30 Meanwhile the articles discharged into the cooling tank are picked up by the belt 87 and carried to a point removed from the tank where they drop into chute 99 as the belt passes down over pulley 89. The belt 35 87 may be run at such a speed as to remove substantially all the charge of one bucket before the next bucket discharges its load.

The chute 99 directs the articles into the finishing drum 101 where they are moved 40 along by the rotation of the screw conveyor element 106. In the drum they are subjected to the action of a pickling liquor, washed, treated by a soda solution and a soap solution and dried. The pickling liquor 5 removes the scale; the soda solution serves to neutralize such pickling liquor as may remain after washing, and the soap solution assists in neutralizing any traces of pickling liquor and leaves a film which, when dried, 50 prevents tarnishing and assists passage of the article in the next drawing operation. The articles are finally discharged from the drum by chute 117 which may direct them to any suitable receptacle or conveyor.

55 The plant above described is capable of suitably effecting the treatment of metal articles and particularly treatment following a drawing operation and in preparation for a subsequent drawing or forming operation. The plant is adapted to effect this treatment in an efficient manner and without harm to the articles. Further, the entire operation from the time the articles are delivered to the hopper to the discharge from 60 the finishing drum is automatic.

Certain features here shown are claimed in the copending application above referred to.

What I claim is:

1. In a plant for treating metal articles, 70 the combination with a heating furnace, of means for automatically delivering the articles thereto, a cooling tank, a conveyor for transporting the articles through the furnace at a rate to enable the heat treatment 75 to be accomplished and delivering them automatically to the cooling tank, a conveyor for automatically delivering the articles from the cooling tank, and finishing means, including means for applying a pickling liquor, then washing, then applying a soda solution and a soap solution, to the action of which the articles are automatically subjected after delivery from the cooling tank.

2. In a plant for treating metal articles, 85 the combination with a heating furnace, of means for automatically delivering the articles thereto, a bucket chain for conveying the articles through the furnace at a rate to enable the heat treatment to be accomplished, pulleys over which said chain passes, 90 a cooling tank located below one pulley and into which the articles may fall by gravity as the buckets pass over said pulley, a conveyor for automatically elevating the articles from the cooling tank, finishing means to which the articles are automatically delivered by said conveyor, and including means for applying a pickling liquor, a washing liquor, a soda solution and a soap solution, 100 to the successive action of which the articles are automatically subjected.

3. In a plant for treating metal articles, the combination with a heating furnace, of 105 an endless conveyor for transporting the articles through the furnace at a rate to enable the heat treatment to be accomplished, pulleys over which said conveyor passes, a cooling tank located below one pulley and 110 into which the articles may fall by gravity as the conveyor passes over said pulley, a conveyor for automatically delivering the articles from the cooling tank, and finishing means to the action of which the articles are automatically subjected after delivery from 115 said last named conveyor.

4. In a plant for treating metal articles, the combination with a heating furnace, of means for automatically delivering the articles thereto, a cooling tank, a conveyor for transporting the articles through the furnace at a rate to enable the heat treatment to be accomplished and delivering them automatically to the cooling tank, a conveyor 120 for automatically delivering the articles from the cooling tank, and finishing means to which the articles are automatically delivered by said second conveyor and to the action of which the articles are automatically 125 subjected after delivery thereto.

5. In a plant for treating metal articles, the combination with a heating furnace, of an endless conveyor for transporting the articles through the furnace at such speed as to enable the heat treatment to be accomplished, means for automatically delivering the articles to said conveyor, pulleys over which said conveyor passes, and a cooling tank located below one of said pulleys and 10 into which the articles may drop by gravity as the conveyor passes over said pulley.
6. In a plant for treating metal articles, the combination with a heating furnace, of a chain of conveyor buckets for transporting the articles through the furnace at such speed as to enable the heat treatment to be accomplished, means for automatically delivering the articles to said buckets, pulleys over which said chain passes, and a cooling 15 tank below one of said pulleys and into which the articles may fall by gravity as a bucket passes over said pulley.
7. In a plant for treating metal articles, the combination with a heating furnace, of an endless conveyor for transporting the articles through the furnace at such speed as to enable the heat treatment to be accomplished, pulleys over which said conveyor passes, and a cooling tank located below one 20 of said pulleys and into which the articles may drop by gravity as the conveyor passes over said pulley.
8. In a plant for treating metal articles, the combination with a heating furnace, of a cooling tank for containing liquid located adjacent the rear end of the furnace, means for transporting the articles through the furnace at such speed as to enable the heat treatment to be accomplished and automatically dumping them into said cooling tank, an endless conveyor having one end located in said tank to be below the liquid level and having means for engaging the articles in the liquid to deliver them from the tank, 30 and means for preventing the articles from floating on the surface of the liquid.
9. In a plant for treating metal articles, the combination with a heating furnace, of a cooling tank for containing liquid located adjacent the rear end of the furnace, means for transporting the articles through the furnace at such speed as to enable the heat treatment to be accomplished and automatically dumping them into said cooling tank, an endless conveyor having one end located in said tank to be below the liquid level and having means for engaging the articles in the liquid to deliver them from the tank, and 40 means for directing jets of water against the articles adjacent the surface of the liquid in the tank to prevent the articles from floating on the surface.
10. In a plant for treating metal articles, the combination with a heating furnace, an endless chain of buckets for conveying the 45 articles through the furnace, means for driving the bucket chain at such a speed as to enable the heat treatment to be accomplished, and means for automatically delivering measured charges of the articles to the successive buckets.
11. In a plant for treating metal articles, and in combination, a heating furnace, a plurality of conveyor buckets movable therethrough, means for moving the buckets, 50 means for automatically delivering articles to be treated to said buckets, and means dependent on the relative position of the buckets for controlling the operation of said delivery means.
12. In a plant for treating metal articles, and in combination, a heating furnace, a plurality of conveyor buckets moving therethrough, a hopper having a gate and arranged to deliver articles to the conveyor 55 buckets by gravity when said gate is opened, and means controlled by the relative position of the buckets for opening said gate.
13. In a plant for treating metal articles, and in combination, a heating furnace, means for conveying articles to be treated through said furnace, a hopper having a gate and arranged to deliver articles to the conveyor means automatically when the gate is opened, and means controlled by the relative position 60 of the conveyor means for opening said gate.
14. In a plant for treating metal articles, and in combination, a heating furnace, a chain of conveyor buckets movable therethrough, pulleys over which the buckets pass, means for driving the conveyor chain, a hopper located above the point where the buckets take an upright position and having a dumping gate, whereby articles in the hopper are delivered to the bucket by gravity 65 when the gate is opened, and means dependent on the relative position of the buckets for causing said gate to open.
15. In a plant for treating metal articles, and in combination, a heating furnace, a chain of conveyor buckets movable therethrough, pulleys over which the buckets pass, means for driving the conveyor chain, a hopper located above the point where the buckets take an upright position and having a dumping gate, whereby articles in the hopper are delivered to a bucket by gravity 70 when the gate is opened, and means including an element actuated once for the passage of each bucket into upright position beneath the hopper, for causing said gate to open.
16. In a plant for treating metal articles, and in combination, a heating furnace, a plurality of conveyor buckets moving therethrough, a hopper having a gate and arranged to deliver articles to the conveyor buckets by gravity when said gate is opened, means tending to open said gate, releasable latch means for preventing operation of said opening means, and means controlled by the 75 80 85 90 95 100 105 110 115 120 125 130

relative position of the buckets for releasing said latch means.

17. In a plant for treating metal articles, and in combination, a heating furnace, a plurality of conveyor buckets moving therethrough, a hopper having a gate and arranged to deliver articles to the conveyor buckets by gravity when said gate is opened, means tending to open said gate, a latch element for preventing the operation of said opening means, and an escapement mechanism for tripping said latch element as each bucket takes a receiving position below the hopper.

18. In a plant for treating metal articles, and in combination, a heating furnace, a plurality of conveyor buckets moving therethrough, a hopper having a gate and arranged to deliver articles to the conveyor buckets by gravity when said gate is opened, means tending to open said gate, a latch element for preventing the operation of said opening means, an escapement mechanism for tripping said latch element as each bucket takes a receiving position below the hopper, and means by which the latch may be reset after each tripping operation.

19. In a plant for treating metal articles, and in combination, a heating furnace, a plurality of conveyor buckets moving therethrough, a hopper having a gate and arranged to deliver articles to the conveyor buckets by gravity when said gate is opened, means tending to open said gate, a latch element for preventing the operation of said opening means, a notched escapement wheel moving in unison with the buckets, a spring-pressed dog riding on said wheel, an operating element for tripping said latch, and a connection between said operating element and said dog.

20. In a plant for treating metal articles, and in combination, a heating furnace, a plurality of conveyor buckets moving therethrough, a hopper having a gate and arranged to deliver articles to the conveyor buckets by gravity when said gate is opened, means tending to open said gate, a latch element for preventing the operation of said opening means, an operating element for tripping said latch, a notched escapement wheel moving in unison with the buckets, a spring-pressed dog riding on said wheel, and a separable connection between said dog and the operating element whereby the latch may be reset as soon as it has been tripped regardless of the position of the dog.

21. In a plant for treating metal articles, and in combination, a heating furnace, a plurality of conveyor buckets moving therethrough, a hopper having a gate and arranged to deliver articles to the buckets by gravity when the gate is opened, a rock shaft, a connection between the gate and the

rock shaft, a weighted arm mounted on the rock shaft and arranged to be raised when the gate is closed, whereby the weight tends to swing down and open said gate, a latch element for holding said weight raised, and means for tripping said latch.

22. In a plant for treating metal articles, and in combination, a heating furnace, a plurality of conveyor buckets moving therethrough, a hopper having a gate and arranged to deliver articles to the buckets by gravity when the gate is opened, a rock shaft, a connection between the gate and the rock shaft, a weighted arm mounted on the rock shaft and arranged to be raised when the gate is closed, whereby the weight tends to swing down and open said gate, a latch element for holding said weight raised, and means controlled by the relative position of the bucket for tripping said latch.

23. In a plant for treating metal articles, and in combination, a heating furnace, a plurality of conveyor buckets moving therethrough, a hopper having a pair of complementary gates and arranged to deliver articles to the conveyor by gravity when the gates are opened, a rock shaft on which one gate is mounted, a connection between the rock shaft and the other gate for causing simultaneous gate movement, a weighted arm mounted on the rock shaft and arranged to be raised when the gates are closed, whereby the weight tends to swing down and open said gates, a latch element for holding said weight raised, and means controlled by the relative position of the buckets for tripping said latch.

24. In a plant for treating metal articles, and in combination, a heating furnace, a plurality of conveyor buckets moving therethrough, a hopper having a gate and arranged to deliver articles to the buckets by gravity when the gate is opened, means tending to open the gate, a latch for preventing operation of said opening means, an escapement wheel moving in unison with the buckets, a dog riding on said escapement wheel, a connection between said latch for tripping the latter and including two separable blocks, a catch for causing said blocks to move as a unit, and means for tripping said catch at the end of the latch tripping stroke, whereby the latch may be reset regardless of the position of the escapement dog.

25. In a plant for treating metal articles, and in combination, a heating furnace, a plurality of conveyor buckets movable therethrough, a measuring hopper having a capacity substantially that of one bucket and having a gate, the hopper being arranged to deliver the articles to the conveyor buckets by gravity when the gate is opened, means tending to open the gate, latch means for

preventing operation of the opening means, and means controlled by the relative position of the buckets for tripping said latch.

26. In a plant for treating metal articles, and in combination, a heating furnace, a plurality of conveyor buckets movable therethrough, a measuring hopper having a capacity substantially that of one bucket and having a gate, the hopper being arranged to deliver the articles to the conveyor buckets

by gravity when the gate is opened, means tending to open the gate, latch means for preventing operation of the opening means, means controlled by the relative position of the buckets for tripping said latch, and means for delivering articles to the hopper.

In testimony whereof, I have hereunto set my hand.

DAVID L. SUMMEY.
